VENETIAN BLIND

Sigfrid Emanuel Lidin, Stockholm, Sweden, assignor to Aktiebolaget Åtidabergs Industrier, Åtidaberg, Sweden, a corporation of Sweden

Application June 15, 1945, Serial No. 599,619
In Sweden April 21, 1944

6 Claims. (Cl. 160—115)

1

The present invention relates to Venetian blinds of the type in which a plurality of horizontal laths are carried upon tapes extending transversely between outer and inner zigzag-ribbons, and are lifted and lowered by means of cords carrying a horizontal bottom piece extending under the laths.

One object of the invention is to reduce the volume of the blind when in raised position, so that the raised blind does not reduce the area of the light.

Another object of the invention is to increase the resistance and the life or the durability of the zigzag-ribbons, more particularly of the outer ribbons subjected to the action of the sun.

A further object of the invention is to produce a thin and narrow construction, yet one having an increased strength.

Two embodiments of a Venetian blind according to the invention are by way of example illustrated in the annexed drawing.

Fig. 1 is a front view of the first embodiment of the blind, partly lowered or let down.

Fig. 2 is a front view of a part of the blind according to Fig. 1 but on an enlarged scale.

Fig. 3 is a vertical cross section on the line III—III in Fig. 2.

Fig. 4 shows a detail of Fig. 2 on an enlarged scale.

Fig. 5 is a front view of a part of a second embodiment of the blind.

Fig. 6 shows a vertical cross section on the line VI—VI in Fig. 5.

The Venetian blind of the present type is preferably intended to be mounted between the panes of a double window, that is, a window having double sashes, but it may be mounted inside the window and even outside the same.

In its general form the Venetian blind according to the invention comprises pairs of zigzag-ribbons or strings, the strings of each pair lying on either side of the blind and each string consisting of a train of rigid sections, as well as joints interconnecting the sections of each zigzag-string, the axes of these joints being perpendicular to the plane of the blind or window.

In the drawing, in Figs. 1 through 3, the reference numeral 1 indicates the top piece from which the blind is suspended, and 2 is a bottom piece extending under the laths represented by 3. The bottom piece preferably has a U-shaped cross-section, so that it encloses and covers the laths 3 when lifted. Between the top piece 1 and the bottom piece 2 two pairs of zigzag-ribbons 4 extend vertically, the ribbons of each pair lying

5 on either side of the blind. According to the invention these ribbons consist of sections of rigid or stiff material, which sections are interconnected by means of hinges or joints. This can be attained in a simple way by the use of a usual flat textile ribbon or webbing which is folded at suitably spaced points 5, transverse seams 6 (Fig. 4) being stitched near the folds to form the joints, whereupon the ribbon is treated with a stiffening or impregnating matter, such as the usual starch, so that the ribbon is made rigid. The flat cross-sections of the ribbons 4 are perpendicular to the plane of the blind.

The transverse tapes 7 which interconnect the 15 ribbons 4 of each pair and upon which the laths 3 rest, are sewed or fastened to the ribbons 4 by means of seams, as illustrated especially in Figs. 2 and 3. Thus, the tapes 7 are laid flat upon the ribbons 4 in spaced relation and then they are 20 stitched to the same. In the zigzag-line which is formed by the ribbons when the blind is lifted wholly or partly, the tapes 7 preferably lie on the undersides of the sections of the ribbons 4. In Fig. 1 the positions of the tapes are marked by the 25 lines 7.

The device described operates into the following manner:

For the lifting and the lowering or letting down of the blind a pair of cords 11, wires or similar 30 means are arranged in suitable or known manner. When the bottom piece 2 is lifted against the top piece 1, the ribbons 4 will fold into the zigzag-form, the sections of the ribbons lying flat on each other, so that the folded ribbon will occupy a 35 minimum of room or space. The bending of the ribbons 4 occurs only at the joints formed by the seams 6. Thus, the ribbons cannot get entangled or twisted or place themselves irregularly. The starching of the ribbons assists in 40 making the folding of the ribbons into zigzag-form entirely reliable. During the lifting of the blind no parts of the zigzag-ribbons place themselves between the laths 3 but they always lie entirely alongside the packet of laths. Thus, in the 45 lifted position the laths 3 are separated only by the transverse tapes 7. Therefore, in lifted position the packet of laths will occupy a most restricted space or room, the volume of the packet of laths in lifted position being reduced to $\frac{1}{3}$ or $\frac{1}{2}$ compared with prior constructions. The volume of the blind in lifted position is reduced further by the U-shape of the bottom piece which thereby obtains the necessary strength without increasing the vertical extension of the packet 50 of laths and bottom piece. The vertical flanges

or branches of the U-profile enclose the packet of lifted laths, so that this packet and the ribbons are covered and hidden or concealed from persons in the room. Because the ribbons 4 are arranged perpendicularly to the plane of the window, the important advantage is obtained that only a very narrow area of the ribbon is faced or turned to the sun, so that the ribbons are not damaged by the sun in the same degree as ribbons lying parallel to the plane of the window. Thus, the durability or the life of the ribbons is increased essentially, especially on the outer side of the window.

In the embodiment shown in Figs. 5 and 6, the zigzag-ribbons 14 are composed of sections of metal strips, for instance, strips of stainless steel, which sections are interconnected by means of joints or hinges 18, the axes of which are perpendicular to the plane of the window. In this embodiment the transverse tapes 17 preferably consist of wires, for instance made of stainless steel. Also the laths 3 and the lifting members 11 may be made of a metal. Thus the elements 11 may consist of stainless steel wires or piano wires. By such construction the blind obtains an increased resistance to the influence of the weather or the atmospheric conditions and therefore can be disposed even on the outer side of the window.

The manner of operation is substantially the same as described in connection with the first embodiment shown in Figs. 1 through 4.

What I claim is:

1. A Venetian blind, comprising, in combination, a plurality of horizontal laths, a horizontal bottom piece extending under the laths, a number of lifting and lowering cords carrying the bottom piece, pairs of zigzag-strings, the strings of each pair lying on the respective sides of the blind and each string consisting of a train of rigid sections, joints interconnecting the adjacent sections of each zigzag-string and the axes of these joints being perpendicular to the plane

of the blind, and transverse tapes interconnecting the zigzag-strings of each pair, the laths resting upon the tapes.

2. A Venetian blind, comprising, in combination, a plurality of horizontal laths, a horizontal bottom piece extending under the laths, a number of lifting and lowering cords carrying the bottom piece, pairs of zigzag-ribbons, the ribbons of each pair lying on the respective sides of the blind and each ribbon consisting of a train of rigid sections which have flat cross-sections perpendicular to the plane of the blind, joints interconnecting the successive sections of each zigzag-ribbon and the axes of these joints being perpendicular to the plane of the blind, and transverse tapes interconnecting the zigzag-ribbons of each pair, the laths resting upon the tapes.

3. A Venetian blind, as claimed in claim 2, wherein, a plurality of transverse tapes are arranged on each section of the zigzag-ribbons in spaced relation to each other.

4. A Venetian blind as claimed in claim 2, wherein the tapes have a flat cross-section and lie in substantially the same plane as the flat sections of the zigzag-ribbons.

5. A Venetian blind as claimed in claim 2, wherein the zigzag-ribbons consist of folded webbings having transverse stitched seams at the folds to form the joints.

6. A Venetian blind as claimed in claim 2, wherein the bottom piece has a U-shaped cross-section.

SIGFRID EMANUEL LIDIN.
